UNITED STATES PATENT OFFICE

FRED GLAHE, OF CHICAGO, ILLINOIS, ASSIGNOR TO A. G. SPALDING & BROS., OF NEW YORK, N. Y., A CORPORATION OF NEW JERSEY

SHOULDER PAD

Application filed August 14, 1929. Serial No. 385,866.

The present invention relates to protective devices for players and embodies, more specifically, an improved form of shoulder pad which is worn by a player to afford greater protection than heretofore available in devices of this character.

The use of shoulder pads of the character embodied herein is most important in connection with the game of football wherein the body of the player is frequently subjected to severe blows. Affording a padding, sufficient to absorb the shocks of such blows, has been the objective of all shoulder pad designs and the consideration of weight and size has seriously hampered the use of pads for adequately protecting the body. The quantity of padding necessary to protect, fully, against the impact of severe blows is such that the weight thereof is quite objectionable and the size such as to be far too bulky to be used successfully.

An object of this invention is to provide a protective device which is light in weight and highly effective to distribute and absorb the severe blows received during play.

A further object of the invention is to provide a device of the above character, the size of which is small in order that it may offer no objectionable bulk to the player.

30 A further object of the invention is to provide a construction of the character described above which combines lightness in weight and compactness in size with a means for cushioning and distributing the blows by means of air pockets.

Further objects, not specifically enumerated above, will be apparent as the invention is described in greater detail in connection with the accompanying drawings; wherein:

40 Figure 1 is a perspective view showing one half of a shoulder pad constructed in accordance with the present invention.

Figure 2 is a view in section taken on line 2—2 of Figure 1, and looking in the direction 45 of the arrows.

Figure 3 is a view similar to Figure 2 showing a modified form of the invention.

Referring to the above drawings, *a* designates the body portion of the pad which is 50 formed with a recess *a'* to accommodate the

neck of the wearer. Lacing tabs *a²* are provided on the vertical edges *a³* of the body to enable it to be laced to a similar pad for the other shoulder.

The outer layer *a⁴* of the pad is formed of 55 relatively soft leather or similar material and lined with a layer of rubber *e* which serves as a base or reinforcement for a layer of sponge or foam rubber *a⁵*. An inner layer *a⁶* of gauze, felt, or other suitable substance is secured over the sponge rubber and sewed directly to the outer layer, thus forming a 60 pocket within which the sponge rubber is received in order that the stitches will not have to pass through the sponge rubber.

Adequate protection is afforded the player by inserting, within the structure recited above, an effective protecting device which embodies air pockets for cushioning the 65 blows received. In order that the above may be attained, the outer layer *a⁴* is formed with apertures *a⁷* and *a⁸*, these apertures being located at the portions of the device where protection is most vitally needed. Discs *b* of relatively stiff and nonyielding 70 leather are formed with cup-shaped depressions *b'* across which the sponge rubber lining *a⁵* is stretched. Stitches *b²* extend around the aperture and pass through the underlying portions of the discs *b* to secure 75 the sponge rubber lining thereto.

It will be apparent, therefore, that an air pocket is formed between the cup-shaped portions *b'* and the sponge rubber lining. These cup-shaped pockets will effectively absorb the blows received at the corresponding points and the escape of air therefrom may be controlled by means of bleed ports *b³*. The discs *b* are made to conform with the outline 80 of the body *a* of the device as will be readily apparent from the drawings.

Shoulder portions *c* are hinged to the sides of the portions *a* at *c'* and are formed of a relatively stiff and non-yielding outer portion *c²* and an inner layer of sponge rubber 85 *c³*. This inner layer is stitched to the outer layer *c* around the periphery thereof, suitable protective strips *c⁴* being provided to prevent cutting of the sponge rubber by the stitching *c⁵* which secures the inner and outer layers 90 100

together. A cup-shaped depression c^6 is formed in the outer layer and provided with a bleed port c^7 . The pocket formed between the inner and outer layers and enlarged by the depression c^6 provides an air column which is confined between the inner and outer layers, thus effectively cushioning blows upon the shoulder.

Over the shoulder and upper portion of the device, an additional pad is provided which cushions the blows upon the top of the shoulder and distributes them between the shoulder and body portions of the pad respectively. This additional cushioning means d is hinged to the body a by a flap d' which is secured under the stitching at the inner extremity of the upper aperture a^8 and is formed of an outer layer d^2 of relatively stiff and non-yielding material, and an inner layer d^3 of sponge rubber. The layers are secured together by stitching d^4 , in a manner similar to the shoulder portion c of the device and the outer layer is formed with a cup-shaped portion d^5 having a bleed port d^6 .

From Figure 2, it will be readily apparent that a blow received by the pad d will be distributed between the shoulder pad c and the upper portion of the body a of the protective device. The escape of air from the air pockets described above may be varied to give the desired cushioning effect. It is contemplated that the stitching which secures the layers together may be of such character as to afford the desired escape without the provision of bleed ports as shown herein. On the other hand, in addition to the stitching, the layers may be glued, cemented or otherwise secured to provide an air-tight connection and thus confine the air in the pockets more effectively.

The construction shown in Figure 3 is similar to that shown in Figure 2 except that the layer of rubber e is omitted.

While the invention has been described in connection with the accompanying drawings, it is apparent that changes in form and design may be made. The materials used may be any of the many available ones and the invention is not to be limited, save as defined in the appended claims.

I claim as my invention:

1. A protective device of the character described comprising an outer portion of relatively non-rigid material having apertures at desired points, cup-shaped portions of relatively rigid and fluid tight material in the apertures, a relatively flexible and fluid tight inner portion, and means to secure the inner portion to the periphery of the cup-shaped portion, and spaced therefrom to form an air pocket between the portions.

2. A protective device of the character described comprising a plurality of sections conforming to a desired contour and secured together, each section being formed of a relatively rigid outer layer and a relatively non-

rigid and flexible inner layer normally spaced from and secured to the outer layer around the periphery thereof in a substantially air-tight fashion to form an air pocket, and an outer section formed of inner and outer layers with an intervening air pocket, the section overlying certain of the first sections to distribute an impact between said first named sections, all of the sections having bleed ports to permit a restricted flow of air from the pockets.

3. A protective device of the character described comprising a plurality of sections conforming to a desired contour and secured together, each section being formed of a relatively rigid outer layer and a relatively non-rigid and flexible inner layer normally spaced from and secured to the outer layer around the periphery thereof in a substantially air-tight fashion to form an air pocket, and an outer section formed of inner and outer layers with an intervening air pocket, the section overlying certain of the first sections to distribute an impact between said first named sections.

4. A protective device of the character described comprising a plurality of sections conforming to a desired contour and secured together, each section being formed of a relatively rigid outer layer and a relatively non-rigid and flexible inner layer normally spaced from and secured to the outer layer around the periphery thereof in a substantially air-tight fashion to form an air pocket, and an outer section overlying certain of the first sections.

5. A protective device of the character described comprising a plurality of sections conforming to a desired contour and secured together, each section being formed of a relatively rigid and fluid tight outer layer and a relatively non-rigid fluid tight and flexible inner layer normally spaced from and secured to the outer layer around the periphery thereof in a substantially air-tight fashion to form an air pocket within which air may be compressed.

6. A protective device of the character described comprising an outer relatively rigid and fluid tight portion conforming generally to a desired contour, an inner fluid tight portion secured to the outer portion around the periphery thereof and normally spaced therefrom to form an air pocket, the portions being secured together in a substantially air-tight manner, and a bleed port for permitting a restricted flow of air from the pocket.

This specification signed this 13th day of May, A. D. 1929.

FRED GLAHE.
